US00D943663S

(12) **United States Design Patent** (10) Patent No.: US D943,663 S
Mortimer (45) Date of Patent: ** Feb. 15, 2022

(54) **TYPEFACE**

(71) Applicant: **QQandU, LLC**, Stansbury Park, UT
(US)

(72) Inventor: **Kenny Mortimer**, West Jordan, UT
(US)

(73) Assignee: **QQandU, LLC**, Stansbury Park, UT
(US)

(**) Term: 15 Years

(21) Appl. No.: **29/782,182**

(22) Filed: **May 4, 2021**

(51) LOC (13) Cl. 18-03

(52) U.S. Cl.

USPC D18/24

(58) **Field of Classification Search**

USPC D18/24, 29, 30, 31, 32; 101/398, 399

CPC B41B

See application file for complete search history.
